DECANTER

Ernest L. Du Pree, New York, N. Y., assignor to Schenley Industries, Inc., New York, N. Y., a corporation of Delaware

Application August 12, 1958, Serial No. 52,182

Term of patent 14 years

(Cl. D58—8)

Figure 4 is an enlarged fragmentary detailed view of the surface ornamentation on the body of the decanter which continues uniformly around the center of the decanter, as indicated on Figure 1; and

I claim:

The ornamental design for a decanter, as shown and described.
